UNITED STATES PATENT OFFICE.

ROBERTO FRITZ EMIL OKRASSA, OF ANTIGUA, GUATEMALA.

BOILER.

1,218,453.

Specification of Letters Patent.

Patented Mar. 6, 1917.

Application filed July 28, 1916. Serial No. 111,845.

To all whom it may concern:

Be it known that I, ROBERTO FRITZ EMIL OKRASSA, a subject of the German Emperor, and a resident of Antigua, Guatemala, Central America, have invented a new and Improved Boiler, of which the following is a full, clear, and exact description.

The object of the invention is to provide a new and improved boiler arranged without an ash pit within the boiler and capable of being used for the generation of dry or wet steam as desired.

In order to accomplish the desired result, use is made of a combined hollow superheater and deflector located at the rear end of the shell for directing the products of combustion from the fire box to the return flues and for generating steam in the said superheater and deflector. Use is also made of a tubular fire box arranged within the shell.

A practical embodiment of the invention is represented in the accompanying drawings forming a part of this specification, in which similar characters of reference indicate corresponding parts in all the views.

Figure 1 is a longitudinal central section of the boiler with the parts in position for generating superheated steam;

Fig. 2 is a rear end elevation of the same with parts of the combined superheater and deflector in section on the line 2—2 of Fig. 1; and

Fig. 3 is a sectional plan view of the same on the line 3—3 of Fig. 2.

The boiler shell 10 is provided with the ends or heads 11 and 12 connected with each other by the usual return flues 13. Within the shell 10 is arranged a tubular fire box 14 which rests upon rectangular frames 15 in the bottom of the casing. Four frames are preferably employed and they are spaced apart to form longitudinal and transverse channels, and the frames are provided with apertures 19, which register with the openings 17 and 18 in the bottoms of the casing and fire box. The grate bars 20 rest upon the frames 21 and between the said frames and resting upon the frame 15, over the transverse channel 16, is the hollow reinforcing grate supporting member 22, in which is the water feed pipe 24. A pipe 25 leads from the channel 16 for drawing off the sediment. Within the transverse and longitudinal channels are arranged stirrer rods 90 and 95 respectively, to stir up the sediment therein. The rod 90 is adapted to be operated by the handle 94 and the rod 95 by the lever 97. The above described construction forms the subject matter of the divisional application filed December 23, 1916, Serial No. 138,686.

The construction shown at the bottom of the fire box in Fig. 1 forms no part of the present invention.

The rear end of the fire box 14 connects, by the fire box flue 30, with a return compartment 31 formed by the shell head 12 and a combined superheater and deflector 40 attached to the head 12 by screws 41 or other suitable fastening means, as plainly indicated in Figs. 2 and 3. The combined superheater and deflector 40 is formed by spaced boiler plates 42, 43 and the frame 44 for holding the plates spaced apart with a view to form a separate boiler or superheater at the end of the shell 10. A pipe 45 having a valve 46 connects the water compartment of the shell 10 with the interior of the superheater and deflector 40 to fill the latter with water to the level of the water in the shell 10 whenever the boiler is used for generating wet steam and the valve 46 is open. For generating dry steam the valve 46 is closed. Within the superheater and deflector 40 are arranged vertically disposed baffle plates 50, 51 and 52 to insure circulation of the steam within the superheater and deflector, as hereinafter more fully explained. The bottom of the superheater and deflector 40 is provided with a manhole 53 for gaining access to the compartment 31 for cleaning out soot and the like. The top of the combined superheater and deflector 40 is provided with a steam outlet pipe 60 having a valve 61 from which leads a pipe 62 for conducting the superheated or wet steam to the desired place of use. The top of the shell 10 is provided with an outlet pipe 70 having a valve 71 connected by a pipe 72 with the pipe 62. The pipe 70 is connected by steam pipes 73 with the interior of the combined superheater and deflector 40 at the sides of the baffle plates 50 and 52, as plainly indicated in Fig. 2. When the boiler is in use and the valves 46 and 71 are closed and the valve 61 is open then the steam generated in the shell 10 passes by way of the pipes 70 and 73 into the combined superheater and deflector 40 in which the steam is caused to circulate by the use of the baffle plates 50, 51 and 52, as indicated

by the arrows in Fig. 2. The steam by coming in contact with the highly heated inner plate 42 is quickly superheated and passes out of the combined superheater and deflector by way of the pipe 60, valve 61 and pipe 62. The valve 71 is closed when it is desired to use the superheated steam from the superheater and deflector 40, but when it is desired to use wet steam then the valve 10 61 is closed and the valve 71 is opened so as to allow the steam generated in the shell 10 to pass by way of the pipe 70, valve 71, pipes 72 and 62 to the place of use.

It is understood that when the boiler is 15 in use the products of combustion from the burning fuel in the fire box 14 pass by way of the flue 30 into the compartment 31 in which the products of combustion are deflected by the superheater and deflector 40 so 20 as to pass through the return flue 13 to the usual breeching 80 arranged on the front end of the boiler.

It will be noticed that the products of combustion in passing into the compartment 25 31 highly heat the combined superheater and deflector 40 so that the water is quickly converted into steam and the steam generated in the shell 10 can pass into this superheater and deflector 40 by way of the 30 pipes 73 in case the valve 71 is closed and the valve 61 is open.

The boiler shown and described is very simple and durable in construction and can be cheaply manufactured.

Having thus described my invention, I 35 claim as new and desire to secure by Letters Patent:—

1. A boiler, comprising a shell, a fire box 40 built in the shell, a flue leading from the rear of the fire box to the rear end of the shell, return flues above the fire box and extending from the rear end of the shell to the front end thereof, a combined hollow superheater and deflector concave on its inner face and comprising spaced plates secured at their edges to the rear end of the shell, the superheater and deflector forming with the said end of the shell a return 45 compartment through which the products of combustion are directed from the said fire box tube to the said return flues, a valved water pipe connecting the water compartment of the shell with the interior of the said combined superheater and deflector at 50 one side thereof to supply the latter with water, a valved outlet pipe leading from the top of said superheater and deflector at the central portion thereof, a valved outlet pipe

leading from the top of said shell and having a valve chamber and valve, the valve 60 chamber being connected by a pipe with the outlet pipe leading from the superheater and deflector, and steam pipes connecting the outlet pipe leading from the top of the shell with the steam compartment of 65 the superheater and deflector at opposite sides thereof, the bottom of the superheater and deflector being provided with a manhole for gaining access to the said return compartment.

2. A boiler comprising a shell, a fire box in the shell, a flue leading from the rear of the fire box to the rear end of the shell, return flues above the fire box and extending from the rear end of the shell to the front 75 end thereof, a combined hollow superheater and deflector on the rear end of the shell and forming with the said end of the shell a return compartment for directing the products of combustion from the said fire box 80 tube to the said return flues, a valved water pipe connecting the water compartment of the shell with the said combined superheater and deflector to supply the latter with water, a valved steam outlet pipe leading from the top of the superheater and deflector, an outlet pipe leading from the top of the shell and having a valve connected by a pipe with the said outlet pipe leading from the superheater and deflector, vertical baffle plates in the said superheater and deflector, and steam pipes connecting the outlet pipe leading from the top of the shell with the interior of the superheater and deflector at the outer sides of the outer baffle 95 plates.

3. A boiler comprising a shell having an outwardly flanged head fitting within the rear end of the shell, a fire box built in the shell, a flue leading from the rear of the fire 100 box to the rear end of the shell, return flues above the fire box and extending from the rear end of the shell to the front end thereof, and a combined hollow superheater and deflector consisting of spaced boiler plates 105 and a frame for holding the plates spaced apart, the said superheater and deflector being concave on its inner face and the edges of the said plates and the said frame extending within the flange of the head and engaging the rear end of the shell, and fastening means extending through the shell and the flange of said head and engaging the superheater and deflector to secure the same in position on the shell.

ROBERTO FRITZ EMIL OKRASSA.
